MODULAR POWER SUPPLY

James P. Ettinger and Christian S. Otteson, Ridgefield,
Conn., assignors to Electric Regulator Corporation,
Norwalk, Conn., a corporation of New York

Filed Apr. 25, 1967, Ser. No. 6,838

Term of patent 14 years

(Cl. D26—15)

FIG. 1

FIG. 1 is a three-quarter perspective view of a modular power supply separate from its enclosure and mounting;

FIG. 2 is a front elevational view, on a reduced scale, of the modular power supply of FIG. 1, the power supply being illustrated engaged within a conventional enclosure which is shown in broken lines;

FIG. 3 is a top plan view of the modular power supply of FIG. 2, taken along the line 3—3 of FIG. 2; and

FIG. 4 is a side elevational view thereof taken along the line 4—4 of FIG. 2.

The dominant features of my design reside in the portions shown in full lines; the broken line showing of a conventional enclosure is shown in FIGS. 2, 3 and 4 for illustrative purposes only.

We claim:

The ornamental design for a modular power supply, as shown and described.
